ATTORNEYS.

UNITED STATES PATENT OFFICE.

JOHN T. MCKENNA, OF NEW YORK, N. Y.

GARMENT HANGER.

Application filed May 12, 1924. Serial No. 712,507.

To all whom it may concern:

Be it known that I, JOHN T. MCKENNA, a citizen of the United States, residing at New York city, county and State of New York, have invented a certain new and useful Garment Hanger, of which the following is a specification.

This invention is a garment hanger adapted to support coat and trousers or vest and 10 trousers. The construction consists in two supporting elements, one of which is adapted to support a coat or vest and the other of which is mounted on the first supporting element and is adapted to support the trousers. The invention is particularly directed 15 to novel and efficient means for detachably mounting the trouser supporting element on the coat or vest supporting element to provide a simple and economical assembly, highly efficient for its intended purposes and 20 convenient and accessible in use.

In one of its preferrel practical forms, the invention embodies a coat or vest hanger comprising laterally extending arms and associated with the opposite ends of these arms are depending loops preferably of flexible character. The trouser support is in the form of a rod provided adjacent its opposite ends with circumferential grooves and 30 the rod is adapted to be passed through the loops until the loops engage the circumferential grooves so that in this manner the trouser rod is supported by the loops. The loops may be of any suitable material, but 35 it is found in practice that they may be conveniently formed from cord and in the preferred embodiments of the invention, the arms of the vest or coat hanger are so constituted that the opposite ends of each cord 40 may be knotted or tied together and the knots concealed from view so as to produce a neat and pleasing appearance.

The advantage of the construction aside from its economy of manufacture is that it 45 allows the trousers to hang freely and enables the rod to be readily attached and detached when desired.

Features of the invention, other than those adverted to, will be apparent from the hereinafter detailed description and claims, when read in conjunction with the accompanying drawings.

The accompanying drawings illustrate 50 different practical embodiments of the invention, but the constructions therein shown are to be understood as illustrative, only,

and not as defining the limits of the invention.

Figure 1 is a perspective view of a coat hanger embodying the present invention. 60

Figure 2 is a section perspective on the line 2—2 of Figure 1; and,

Figures 3, and 4 are views similar to Figure 2, but showing modified forms of the construction. 65

Referring to the drawings, 1 designates a hanger shaped to support a coat or vest and provided with laterally extending arms 2 suitably configurated to enable it to properly perform its function. 3 is a trouser 70 supporting rod provided adjacent its opposite ends with circumferential grooves 4.

In the various figures of the drawings, different ways are shown for supporting the rod 3 from the hanger 1. In Figures 1 and 75 2, each of the arms 2 of the hanger 1 is shown as provided adjacent its end with a pocket 5 extending upwardly into the arm from the under side thereof and a hole 6 is bored through each arm and intersects the 80 pocket. A cord 7 is formed into a loop by passing the free ends of the cord through the opposite ends of the hole 6 and uniting these ends with a knot 8 positioned within the pocket 5 as shown in Figure 2. The cord 85 loops 7 thus formed depend from the arms 2 and serve as a support for the rod 3. Under normal conditions, these loops are adapted to engage the grooves 4 in such manner as to preclude inadvertent displacement 90 of the rod. However, when it is desired to remove the rod, it may be lifted slightly to permit the loops 7 to be swung free from the ends of the rod and to thus disengage the rod from the said loops. 95

In the modified form of the construction shown in Figure 3, the arms 2 of the hanger 1 are provided with pockets 5 in the same manner as shown in Figure 1 and a hole corresponding to the hole 6 is bored through 100 each arm. In this hole is positioned a pin or dowel 9 and the cord is tied around this dowel on the interior of the pocket, so that the knot is concealed while the loop 7 hangs unobstructedly from each arm and is adapted for engagement with the trouser supporting rod. In the construction of Figure 4 two holes 6 and 6^a are provided in each arm and intersect the pocket 5. The cord is looped as heretofore to form a loop 7, 110 while the opposite ends of the cord are passed inwardly through the opposite ends

of the hole 6 into the pocket 5. The cord is then passed upwardly in the pocket and its free ends passed outwardly through the hole 6^a and thereupon provided with knots 10 which preclude the withdrawal of the free ends of the cord and provide a permanent loop 7 at the end of each arm 2 which functions to support the rod in the same manner as hereinbefore described. The 10 knots 10 may be received in countersunk portions 10^a at the opposite ends of the hole 6^a.

In the several forms of the invention thus far described, cord is employed for the formation of the loops 7 and this is a very satisfactory construction. Rawhide, tape or other suitable flexible material may be employed in this connection, but I prefer that the loops are flexible in that a flexible loop 20 is more readily passed over the rod and more positively supports it while permitting of yielding coaction between the trouser supporting rod and the hanger 1.

The hanger 2 may be provided with any 25 suitable suspension member whereby it may be hung from a fixed support but for the purpose of illustration I have shown a novel and highly efficient suspension means. The means illustrated is in the form of a metallic strap 12, the intermediate portion of which is adapted to be received within a vertical channel 13 formed in one face of the hanger. The upper portion of the strap is bent to form a hook 14 to engage a suitable 30 permanent support while the lower end of the strap 12 is bent rearwardly under the central portion of the hanger 1 as shown at 15 to form a seat on which the hanger is adapted to rest. At the rear end of this 35 seat, the strap is bent downwardly as at 16 and then forwardly at 17 to provide a hook portion on which any desirable article may be hung. The intermediate portion of the strap is provided with elongated slots 18 40 through which screws 19 may be passed so as to enter the base of the channel 13. The purpose of these screws is to bind the hanger 1 to the strap while the purpose of the elongated slots 18 is to permit the hanger to 45 seat on the part 15 so that the weight imposed on the hanger is carried by the seat 15 and is not imposed directly upon the screws as has heretofore usually been the case. This construction is a very strong and 50 durable arrangement and there is no tend-

ency of the screws to pull out even when very heavy garments are hung upon the hanger since the entire weight of the garment is carried on the seat 15.

Having thus fully described the invention, what I claim as new and desire to secure by Letters Patent is:

1. An assembly of the character described embodying a coat or vest hanger provided in one face thereof with a substantially 65 upright channel, a metallic strap seated in the channel and provided with elongated slots, screws passed through said slots into the hanger, said strap being provided on its upper portion with a hook shaped portion and at its lower portion with a seat adapted to engage the under side of the hanger, a trouser supporting rod, and loops mounted on the hanger and depending therefrom to engage the opposite ends of the rod 70 and detachably support the rod on the hanger.

2. In an assembly of the character described, a hanger provided with rigid laterally projecting arms adapted to support 80 a coat or vest, each of which arms is provided on its under side with a pocket, a cord loop extending into each pocket and permanently secured therein with the loops depending exteriorly of the pockets to support a rod at a fixed predetermined distance below the hanger, and a trouser supporting rod, the opposite end portions of which are 85 adapted to seat in the cord loops, and means for precluding inadvertent slipping of the loops from the end of the rod.

3. In an assembly of the character described, a hanger provided with laterally projecting arms adapted collectively to support a coat or vest, a separate and distinct 95 length of cord permanently secured to each arm and depending from each arm in the form of a closed loop, said loops being adapted to collectively support a rod at a fixed predetermined distance below the 100 hanger, and a trouser supporting rod the opposite end portions of which are passed through the loops and are supported from the hanger thereby, said rod being configured to preclude inadvertent slipping of the 105 loops off the ends of the rod.

In testimony whereof I have signed the foregoing specification.

JOHN T. McKENNA.
